CLAIM

The ornamental design for a necktie restraint, as shown and described.

DESCRIPTION

FIG. 1 is a perspective view of a necktie restraint showing my new design;

FIG. 2 is a perspective view, the broken line showing of a portion of a necktie being for illustrative purposes only and forming no part of the claimed design;

FIG. 3 is a front elevational view;

FIG. 4 is a top plan view;

FIG. 5 is a bottom plan view; and

FIG. 6 is a side elevational view.

The design is bi-laterally symmetrical.
